THOMAS J. KEENAN, OF STEUBENVILLE, OHIO

SAFETY VALVE AND DRAIN FOR BOILERS

Application filed April 12, 1929. Serial No. 354,647.

My present invention has reference to a safety valve for house or like small hot water boilers, and the primary object is the provision of a device of this character which 5 is screwed in the boiler and which includes a spring influenced valve that will automatically open by an over pressure of steam in the boiler, and thereby afford a safety device that will prevent the explosion of the 10 boiler.

A still further object is the provision of a device for this purpose in which the valve may be retained in open position, as when it is desired to drain the boiler.

15 To the attainment of the foregoing and other objects which will present themselves as the nature of the invention is better understood, the improvement also consists in certain other novel features of construction, 20 combination and operative association of parts, one satisfactory embodiment of which is disclosed by the accompanying drawings.

In the drawings:

Figure 1 is a side elevation of the improvement in applied position, parts being 25 in section.

Figure 2 is a similar view of the improvement showing the valve moved and locked in unseated position as when the boiler is 30 to be drained.

Figure 3 is a detail sectional view through the center portion of the body of the improvement.

As disclosed by Figure 1 of the drawings 35 I screw in a boiler 1 the reduced and threaded end 2 of the valve body member 3 of the improvement.

The second or outer end of the body is 40 preferably widened and is contacted by a washer which is let in a depression in a flanged cap 4 which is screwed on the said body. The body, at a suitable distance away from the open end that is closed by the cap 4 is inwardly directed and is formed with 45 interior threads 5. In practice I have found that only two of these threads are required. Above the inwardly thickened or flanged threaded portion 5 the body is formed with a chamber 7 that communicates with a port 50 or passage 8 that extends centrally through

the threaded end of the body. The chamber 7 is in communication with a port or passage in a downwardly inclined extension 9 that is integrally formed with the body. This pipe extension 9 preferably has its outer end 55 widened, and the said end is threaded, as at 10, whereby a coupling for a hose may be attached to the body 3.

The wall 11 between the chamber 9 and the passage 8 provides a seat for the preferably compressible face 12 of a valve member 13 which is preferably in the nature of a thickened disc. The lower portion of the valve is provided with threads 14 that are designed when the valve is unseated to engage with the threads 5 as disclosed by Figure 2 of the drawings and thereby open the passage of the extension 9 to the chamber 7 and likewise to the passage 8 in the body. The valve is provided with a stem 15 that 70 passes through the packing ring 16 on the inner face of the flanged cap 4 and likewise passes centrally through the said cap.

The outer end of the stem 15 has attached thereto a handle 17. Surrounding the valve 75 stem and received in the lower chamber of the body and exerting a pressure between the gasket 16 and one end of the valve 13 there is a coil spring 18. This spring is of sufficient strength to normally seat the valve 80 13 when the screw portion thereof does not engage with the interior screws 5 in the body. The spring 18, however, will yield when the valve is influenced by an overpressure of steam in the boiler 1, so that the valve is 85 thus opened and steam will escape through the passage 8, the chamber 7 and the passage in the extension 9 of the body. A downward pressure on the handle 17 will also 90 unseat the valve and a turning of the handle 95 will cause the threads 14 to engage with the interior threads 5 in the body so that the valve is held unseated as disclosed by Figure 2 of the drawings when the boiler is to be drained.

The simplicity and advantages of the construction will, it is thought, be perfectly apparent when the foregoing has been carefully read in connection with the accompanying drawings so that further descrip- 100

tion will not be required. However, I wish it understood that I do not desire being restricted to the precise details herein set forth and, therefore, hold myself entitled to make such changes therefrom as fairly fall within the scope of what I claim.

Having described the invention, I claim:

A device for the purpose set forth comprising a valve body designed to have one end screwed in a boiler, said body having a central chamber therein, a second chamber outward of the central chamber, a flanged cap closing the outer chamber, and interior threads between the chambers, said body also having an angle extension having a passage which communicates with the central chamber, a valve having a compressible facing received in the central chamber and designed to close the passage between the central chamber and the end of the body connected with the boiler, said valve being round in cross section and having threads thereon, a stem extending from the valve and passing through the cap, a handle on the outer end of the stem, and a spring surrounding the stem, arranged in the body and exerting a pressure between the cap and the valve for normally seating the valve, and said valve designed to be unseated when an outward pressure is exerted on the handle and the latter is turned to bring the threads of the valve into coengagement with the interior threads of the body.

In testimony whereof I affix my signature.

35 THOMAS J. KEENAN.
